UNITED STATES PATENT OFFICE

BENJAMIN C. LOCKETT, OF NEW YORK, N. Y., ASSIGNOR TO THE YORK MANUFACTURING COMPANY, OF SACO, MAINE.

DESIGN FOR A PATTERN-CARD.

SPECIFICATION forming part of Design No. 18,481, dated July 24, 1888.

Application filed May 25, 1888. Serial No. 275,042. Term of patent 7 years.

To all whom it may concern:

Be it known that I, BENJAMIN C. LOCKETT, a citizen of the United States, residing in New York city, New York, have invented or produced a new and original Design for a Pattern-Card, of which the following is a specification.

My design for a pattern card is fully shown in the accompanying drawing.

10 The card is rectangular in outline, and has on its face a series of oblong tablets, *a*, which are in line vertically, each tablet being parallel at top and bottom, and having opposite beveled ends likewise parallel. At one of the
15 lower corners of the card is a small inclined tablet, *b*, of wedge shape, and at one of the upper corners of the card is a quadrangular

tablet, *d*. These latter tablets, however, I consider a minor feature of the design, and they may be omitted, if desired.

2c

I claim—

The within-described design for a pattern-card, said design consisting of the rectangular card having a series of parallel tablets, each having parallel beveled ends, said tablets being in line vertically, all substantially as described and shown.

25

In testimony whereof I have signed my name to this specification in the presence of two subscribing witnesses.

BENJ. C. LOCKETT.
